RALPH R. BEAL, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

WIRELESS TELEGRAPHY.

1,320,525.

Specification of Letters Patent. Patented Nov. 4, 1919.

Application filed July 28, 1915. Serial No. 42,298.

To all whom it may concern:

Be it known that I, RALPH R. BEAL, a citizen of the United States, and a resident of Palo Alto, county of Santa Clara, State of California, have invented certain new and useful Improvements in Wireless Telegraphy, of which the following is a specification.

The invention relates to a receiving system for wireless communication and especially to a device adapted to be used in said system.

An object of the invention is to provide an apparatus by means of which continuous electrical oscillations of high frequency are converted into continuous oscillations of lower frequency.

The invention possesses other objects and advantageous features, which, with the foregoing, will be set forth at length in the following description, where I shall outline in full that form of the invention which I have selected for illustration in the drawings accompanying and forming part of the present specification. In the drawings I have shown only one specific form of my generic invention, but it is to be understood that I do not limit myself to such form, because my invention may be embodied in a multiplicity of forms, each being a species of my said invention. It is also to be understood that by the claims succeeding the description of my invention, I desire to cover the invention in whatever form it may be embodied.

Referring to said drawings:

Figure 1 is a perspective view of one form of the device of my invention.

Fig. 2 is a diagrammatic illustration of the operation of the invention.

Fig. 3 is a diagrammatic representation of a receiving circuit including the device of the present invention.

The frequency of the oscillations in a wireless telegraphy system employing continuous undamped waves is so high that it cannot be utilized to operate electromagnetic instruments such as telephone receivers and produce audible signals. The frequency of the oscillations is above the limits of audibility and to be received by the ear the frequency must be reduced to within these limits. This has been accomplished heretofore by arranging an interrupter and a condenser in the receiving circuit, the con-

denser being charged by the high frequency oscillations during the time that the interrupter is closed, and discharging with a surge through the telephone receivers when the interrupter is open.

In accordance with my invention I convert the high frequency current into a current of audible frequency and operate the receivers by this low frequency current. By opening and closing the receiving circuit at a frequency which may be made to approach synchronism with the frequency of the received oscillations, a low frequency current is obtained which flows through the telephones. The regularity of this low frequency current gives a musical note to the received signals, and the nearer that the frequency of interruption approaches the frequency of the incoming waves, the lower will be the note. In Fig. 2 I have shown diagrammatically the incoming undamped oscillations of high frequency 2. The frequency of interruption is somewhat less than the frequency of the oscillations, resulting in a current 3, which is of much lower frequency than that of the incoming waves.

The interruption of the circuit to produce this low frequency is obtained by a vibrating or bouncing conductor which is maintained constantly in motion at a constant frequency. In the present instance the means consists of a wire 4 engaging the surface of a rapidly moving polished surface 5, consisting of the peripheral surface of the wheel 6. The wire is suitably held in a support arranged at the side of the wheel, preferably that side toward which the wheel turns, so that the smooth moving surface 5 is in contact with the end of the wire. In the preferable construction the main portion of the wire lies in a plane substantially parallel with the plane of tangency with the smooth surface at the point of contact with the wire and the free end of the wire is bent toward the surface, so that the end of the wire approaches perpendicularity with the surface at the point of contact. As the wheel rotates, the wire bounces and moves out of and into contact with the wheel at a high and uniform rate. The length and the physical dimensions and properties of the wire are so adjusted that the wire will vibrate at the proper frequency to produce the desired resultant low frequency current. The wire holding support 7 and the wheel 6

are preferably insulated from each other by mounting both on a block 8 of suitable insulating material. The wheel 6 is preferably driven by and insulated from a small electric motor 9 mounted on the same block 8.

The device, indicated at 12 in Fig. 3, is placed in series with the telephone receivers 13 in the secondary circuit 14 of a properly 10 tuned wireless receiving set, of which 15 is the primary or open circuit, one terminal being connected to the wire and the other to the support for the wheel. The high frequency current is converted into a current 15 of lower frequency by the device, and this low frequency current is effective in operating the telephones.

It is not necessary that the frequency of the interruption be near synchronism with 20 the frequency of the received oscillation, and it may be varied to produce any desired note in the telephones.

I claim:

1. In a receiving system for wireless te-
25 legraphy receiving continuous oscillations, a receiving circuit, and means for regularly interrupting the receiving circuit at a frequency less than that of said continuous oscillations comprising an element having a
- 30 smooth surface, a resilient conductor bent to engage said surface and means for moving the surface against the conductor, whereby said conductor is caused to vibrate and make and break contact with said surface.
- 35 2. In a receiving system for wireless te-

legraphy receiving continuous oscillations, a receiving circuit, and means for regularly interrupting the receiving circuit at a frequency approaching synchronism with the frequency of the oscillations comprising a wheel having a smooth surface, a conductor resting on said surface, and means for rotating the wheel against said conductor whereby the conductor is caused to bounce and make and break contact with said wheel, said wheel and conductor being otherwise insulated from each other.

3. In a receiving system for wireless te-
legraphy receiving continuous oscillations, a receiving circuit, and means for regularly interrupting the receiving circuit at a frequency approaching synchronism with the frequency of the oscillations comprising a wheel having a smooth surface, a bent wire contacting with said wheel, the body of the wire lying in a plane parallel to a plane tangential to the wheel at the point of contact of the wire, the contacting end of the wire being bent to engage the surface of the wheel at an angle, and means for rotating said wheel toward said wire whereby the wire is caused to bounce at a regular frequency.

In testimony whereof, I have hereunto set my hand at San Francisco, California, 6 this 12th day of May, 1915.

RALPH R. BEAL.
